CLAIM

The ornamental design for a hard shell blood glucose testing system case, as shown and described.

DESCRIPTION

FIG. 1 is a front plan view of a hard shell blood glucose testing system case;

FIG. 2 is a rear plan view of the hard shell blood glucose testing system case;

FIG. 3 is a top plan view of the hard shell blood glucose testing system case;

FIG. 4 is a bottom plan view of the hard shell blood glucose testing system case;

FIG. 5 is a right-side plan view of the hard shell blood glucose testing system case;

FIG. 6 is left-side plan view of the hard shell blood glucose testing system case;

FIG. 7 is a front perspective view of the hard shell blood glucose testing system case;

FIG. 8 is a rear perspective view of the hard shell blood glucose testing system case;

FIG. 9 is a front bottom perspective view of the hard shell blood glucose testing system case; and,

FIG. 10 is a rear bottom perspective view of the hard shell blood glucose testing system case.

The broken lines in FIGS. 1-10 depict portions of the hard shell blood glucose testing system case that form no part of the claimed design.
